DESIGN.

C. A. POST.

FAN AND CASING.

APPLICATION FILED MAY 29, 1916.

49,546.

Patented Aug. 22, 1916.

UNITED STATES PATENT OFFICE.

CHARLES A. POST, OF SHERIDAN, WYOMING.

DESIGN FOR A FAN AND CASING.

49,546.

Specification for Design.

Patented Aug. 22, 1916.

Application filed May 29, 1916. Serial No. 100,694. Term of patent 14 years.

To all whom it may concern:

Be it known that I, CHARLES A. Post, a citizen of the United States, residing at Sheridan, Sheridan county, State of Wyoming, have invented a new and original and ornamental Design for a Fan and Casing, of which the following is a specification, reference being had to the accompanying drawing, forming a part thereof, in which—

I claim:

The ornamental design for a fan and casing as shown.

CHARLES A. POST.
